(57) **CLAIM**

The ornamental design for a utility knife for horse/bull riders, as shown and described.

DESCRIPTION

FIG. 1 is a front elevational view of a utility knife for horse/bull riders showing my new design;
FIG. 2 is a top plan view thereof;
FIG. 3 is a bottom plan view thereof;
FIG. 4 is a left side elevational view thereof; and,
FIG. 5 is a right side elevational view thereof.
The broken line portion of FIG. 1 is for illustrative purposes only and forms no part of the claimed design.
